UNITED STATES PATENT OFFICE

EUGENE E. AYRES, JR., OF SWARTHMORE, PENNSYLVANIA, ASSIGNOR TO B. A. S. COMPANY, OF PHILADELPHIA, PENNSYLVANIA, A CORPORATION OF DELAWARE

ABSORPTION OF GASOLINE FROM NATURAL GAS

Application filed July 9, 1925. Serial No. 42,392.

My invention relates to a method and an apparatus for the practice thereof, for the absorption of gasoline from natural gas. It has for its object increasing the yield of gasoline, reducing the quantity of oil required for absorption purposes, and reducing the amount of power required for the pumps and stills.

The first step in the manufacture of gasoline from natural gas has, as its aim, the separation of the gas into two parts, namely, (1) hydrocarbons whose boiling points are lower than the normal butane and which constitute the "tail" gases (e. g. methane, ethane, propane, and isobutane), and (2) hydrocarbons whose boiling points are higher than isobutane and which constitute the liquid fraction (e. g. normal butane, pentanes, hexanes). This objective is never completely attained, for, in practice, the "tail" gases always contain some of the higher boiling hydrocarbons, and the liquid fraction always contains dissolved gases, notably propane and isobutane. Later steps in the manufacture of gasoline from natural gas relate to the separation from the gasoline of such objectionable constituents as the propane and isobutane above referred to.

My present invention has to do with an improvement in the first stage of manufacture whereby the "tail" gases will be more completely freed from gasoline hydrocarbons, thus increasing the gross yield of gasoline from natural gas. It relates more particularly to an improvement in oil absorption methods whereby an increased absorption efficiency is obtained without recourse to the usual expensive expedients.

The absorptive medium heretofore most used has been a menstruum of mineral-seal oil, and while it is in connection with the use of this particular absorptive medium that I describe my present invention, I do not intend that my invention shall be limited to its exclusive use.

The method usually employed to bring the absorptive medium into contact with the gas has been to flow the gas and the menstruum counter-current in a suitable tower. The oil is admitted at the top; the gas is admitted at

the bottom, thus the leanest gas is in contact with the freshest oil, and absorption efficiency is limited only by conditions of equilibrium between menstruum and gas. It has been found that an increase of pressure during the period of absorption will increase the absorptive power of the oil, but with the increase of absorptive power, there is an increase in the proportion of undesirable highly volatile substances absorbed by the oil, with resulting "wildness" in the gasoline afterwards distilled from the oil. An increase of pressure, however, has the advantage that less circulation of oil is required with resulting saving in oil handling equipment. The above factors have resulted in practice in the general use of about 30 lbs. pressure in the absorber towers.

It has also been found that a decrease of temperature of the oil increases the absorptive efficiency thereof, with corresponding decrease in the losses of valuable gasoline hydrocarbons in the "tail" gases, and decrease in the total volume of oil necessary. These advantages are not enough to off-set the disadvantage of expensive artificial refrigeration. The result has been in practice that absorption has been conducted at substantially cooling pond temperature.

It has also been found that an increase of circulation (i. e. ratio of oil to gas) will produce an increase in the absorption efficiency but the obvious difficulty is that the increased amount of oil requires an increase in the size of all the oil apparatus.

I have found that in counter-current absorbers for natural gas the oil entering at the top of the tower, encounters a gas from which the heavier constituents have already been removed further down in the tower. Accordingly the fresh oil takes up the lighter constituents, for the most part butane. Further down in the tower the oil encounters a gas composed in greater proportion of heavier constituents such, for example, as pentane. The oil, in absorbing pentane, releases a certain amount of butane which was absorbed higher up in the tower and unless this butane is recaptured nearer the top of the tower it is lost. As the oil approaches

55

100

the bottom of the tower it begins to encounter gas containing in addition to butane and pentane larger and larger percentages of hexane and heavier substances. In absorbing hexane and heavier substances, for which the oil has the greatest affinity, a considerable quantity of the lighter substances (butane and pentane) are liberated. These liberated gases must be recaptured higher in the tower or they will be lost with the "tail" gases.

In any simple counter-current absorption system it is impossible to avoid losses in gross production by this tendency of one hydrocarbon to displace another, no matter how favorable all pertinent conditions may be made.

An object of my invention is the reduction of these losses that are inherent in simple counter-current absorption.

In accordance with my invention, I introduce oil which has been thoroughly "stripped" (i. e. absorbed hydrocarbons thoroughly removed) into the top of one of a pair of absorber towers, which I will refer to as the second absorber. I introduce the gasoline bearing gas at the foot of the other (or first) absorber and flow it in succession through the two absorbers. Though I flow the oil counter-current with respect to the direction of flow of the gas, I do not pipe it directly from the second absorber to the first but in the interval I partially strip it to remove certain of the gases which it has absorbed in the second absorber. The oil upon entering the second absorber encounters therein gas which has already been in contact with the oil in the first absorber. From this gas has already been removed those heavier constituents for which mineral-seal oil has the greatest affinity (hexane and heavier). The oil therefore absorbs the lighter constituents such as pentane and butane which are equally valuable in gasoline. Because of the fact that the oil entering the second absorber is thoroughly stripped, it is of sufficient absorptive capacity to take up successfully these lighter constituents. It is not necessary to use thoroughly stripped oil in the first absorber because at that point it is unnecessary to remove all of the gasoline hydrocarbons. The oil entering the first absorber need, therefore, be only partially stripped. This may be effectually accomplished merely by reducing the pressure at which the oil was maintained in the absorber (usually about 30 lbs.) to atmospheric pressure and then advantageously to about 20 inches vacuum, without raising the temperature. This sufficiently strips the oil to make it a useful absorptive medium when introduced into the first absorber where the richer gas does not require a medium of such high absorptive capacity. The oil emerging from the first

absorber is saturated with those heavier hydrocarbons for which it has the greatest selective capacity. The oil taken from the first absorber is therefore the only oil which need be operated upon by the distillation apparatus. I vent this oil to atmospheric pressure before the oil is operated upon by the usual distilling apparatus.

Among the principal advantages which follow from the use of my invention is the securing of a higher gross yield of gasoline, without an increase of the usual stock of oil. Or, a gross yield (or absorption efficiency) equal to that obtained by ordinary methods can be obtained by use of my invention with a material reduction in the quantity of oil circulated. This produces the incidental advantages that the cooling pond, the still, the circulating gas or steam used in the distillation, and all related power accessories need have less than the usual capacity.

Referring to the accompanying drawings which form a part of this specification,

Fig. 1 shows diagrammatically a simplified form of my invention in which but two absorbers are used; and

Fig. 2 shows diagrammatically a system in which three absorbers are provided.

Referring to Fig. 1, two absorbers 1 and 2 are arranged so that gas enters through pipe 4 near the foot of absorber 1, is removed from a point 5 near the top of absorber 1 by the pipe 6 and introduced at the point 7 near the foot of the absorber 2 and is finally vented from a point near the top of absorber 2 through the pipe 8. Well stripped oil is introduced through the pipe 9 at a pressure of about thirty pounds to the top of absorber 2 and in passage through absorber 2 takes up the residue of the valuable gasoline hydrocarbons remaining in the gas which enters that absorber. The oil, containing these hydrocarbons is removed from absorber 2 by the pipe 10 and introduced to the chamber 3 where it is vented to atmospheric pressure. Such gases as evolve are removed by the pipe 11 to the condensation plant to be treated in the later steps of the manufacture of gasoline. The effect of the release of pressure in chamber 3 is to strip the oil in that chamber with merely a moderate degree of thoroughness. Inasmuch, however, as the oil is now to be used for the absorption of hydrocarbons in absorber 1 for which it has the highest degree of selective absorption capacity, it is not necessary that this stripping be made more thorough. The oil thus stripped is removed from the chamber 3 by the pipe 12 and restored to a pressure of 30 lbs. by the pump 13. It is then delivered by the pipe 14 to the top of absorber 1 where it comes at once into contact with gas rich in the heavier hydrocarbons. Conditions of flow in the absorber 1 are so arranged that the oil as it leaves the foot of absorber 1 will contain the highest possible

percentage of gasoline hydrocarbons, without regard for absorption efficiency, since the gases discharging from absorber 1 may be permitted to contain gasoline hydrocarbons in view of the fact that they are to be passed through absorber 2. The oil issuing from absorber 1 is conveyed by the pipe 15 to the chamber 19 where it is vented to atmospheric pressure and the evolved gases are conveyed through the pipe 20 to the condensation system. The oil is then removed at substantially atmospheric pressure from the chamber 19 and is conveyed through the pipe 21 to the heater 16, the still 17 and the cooler 18. Vapors driven off from the absorption medium in still 17 are passed from the still 17 to the condensation system through pipe 49 while the oil is then restored by the pump 13^a to a pressure of 30 lbs. and passed through pipe 9 to repeat the above cycle.

Referring to Fig. 2 of the drawings, gas is introduced into absorber 22 through the pipe 25 near the foot thereof; it is removed from absorber 22 by pipe 26 and introduced at the point 27 to absorber 28; it is removed from absorber 28 at the point 29 and conveyed by the pipe 30 to a point 31 near the foot of absorber 32; and the tail gases are discharged from a point near the top of absorber 32 through the pipe 33. A thoroughly stripped portion of the main current of oil, at thirty pounds pressure, is introduced at the point 42 through the pipe 41 to absorber 32. This oil is removed from absorber 32 by the pipe 48 and is flowed into the chamber 23, where the pressure is reduced to atmospheric pressure, evolved gases being removed to the condensation system by pipe 45. The effect of this evolution of gas is to produce an oil sufficiently well stripped for introduction into absorber 22, where the gas is richest in heavy hydrocarbons. Accordingly, I convey the oil from chamber 23 through the pipe 24 to the pump 51 where a pressure of 30 lbs. is restored. Thence the oil is conveyed by the pipes 52 and 53 to the top 54 of absorber 22. In absorber 22 the flow of gas and oil is so arranged that the oil issuing from the foot of absorber 22 contains the highest percentage of gasoline that it will absorb. This oil is removed through pipe 55 to chamber 56, where it is vented to atmospheric pressure and the evolved gases are removed by the pipe 43 to the condensing plant. The oil then flows through pipe 57 to a heater 58, thence by the pipe 59 to a still 60. The gasoline hydrocarbons here stripped from the oil are carried by the pipe 79 to the condensing system. The main flow of oil now passes through the pipe 84 to the cooler 35, thence to be carried to absorber 28. A small part of the current of oil flowing out of the still 60, however, is shunted through the pipe 36 to an additional distilling or stripping unit composed of the heater 37, the still 38, and the cooler

40. The gasoline hydrocarbons stripped from the oil in the still 38 are carried by the pipe 50 to the condensing system. This shunt stream is restored by the pump 46 to a pressure of 30 lbs. and is fed through the pipe 41 to absorber 32 to repeat the cycle above set forth. The main stream of oil, not subjected to the combined stripping effect of stills 60 and 38, but merely stripped as well as may be by the use of the single still 60, is restored by the pump 47 to a pressure of thirty pounds and is fed through the pipe 61 to absorber 28 at a point 62 at the top thereof. This oil is removed from absorber 28 at the foot thereof by pipe 63 and is introduced into chamber 64 where it is vented to atmospheric pressure. Such gases as evolve in chamber 64 are taken by pipe 44 to the condensing system. The oil thus partly stripped then flows through pipe 65 to the chamber 66, where it is subjected to a vacuum of approximately twenty inches. This vacuum distillation results in the effervescence of more gas which is drawn off through the pipe 67 and introduced to the condensing plant. The oil now passes through the pipe 68 to the pump 69, where it is restored to a pressure of 30 lbs. and is passed through pipe 70 to a junction with the above-mentioned shunt stream, whence both proceed through the pipe 53 to resume the cycle above described.

In the form of my invention illustrated by Figure 2, therefore, I employ in conjunction with three absorbers a system in which oil is stripped with three degrees of thoroughness. The oil entering the top of absorber 32 is the most thoroughly stripped; that entering the top of absorber 28 is stripped with moderate thoroughness; that entering the top of absorber 22 is poorly stripped. The poorly stripped oil is composed in part of oil which has been through the third absorber and has merely been stripped by venting to atmospheric pressure, and in part of oil which has been through the second absorber but has been stripped by venting to atmospheric pressure and in addition by subjection to vacuum. The medium quality of oil, entering the top of absorber 28, has been stripped by the combined action of venting to atmospheric pressure in tank 56 and heating and distilling and cooling in the still 60 and adjacent apparatus. The best stripped oil, entering the top of absorber 32, has been stripped by the successive effects of venting to atmospheric pressure (tank 56), distilling (still 60), and additional forced distilling at higher temperatures in still 38. Thus, by rearranging somewhat the essential elements contained in the form of apparatus shown in Figure 1, a system employing three absorbers can be utilized. Similarly, systems can be arranged to employ any number of absorbers, using the principles which underlie my invention, and merely

rearranging to a slight extent the piping diagrams shown herewith.

The advantages derived from the practice of my invention as set forth above are many. One important advantage is that the heat distillation plant, whereby gasoline hydrocarbons are stripped from the oil, is required to handle an oil from which a considerable part of the lighter gasoline hydrocarbons have already been stripped by the pressure reduction accompanying the venting of gases in connection with each absorber, and may therefore be of less capacity. One of the methods of stripping gasoline from charged oil, is to flow a current of the lighter hydrocarbons such as propane through the hot oil in the still. If this method of distillation or "stripping" be utilized, it will be found that the relatively high concentration of heavier gasoline hydrocarbons in the charged oil will require the recirculation of a relatively small quantity of gas in order effectually to strip the oil. A similar result follows if steam be used. With the decreased volume of gas or steam thus required, the size of the distilling apparatus may be correspondingly reduced. A further advantage of my improved method, and the apparatus for the practice thereof, is that well stripped oil is used exclusively for the absorption of the lighter hydrocarbons such as butane, which are most difficult to absorb, and these substances are in a large measure recovered from the oil before they are driven out and lost due to the absorption of the heavier hydrocarbons such as hexane, for which the oil has a selective affinity.

My improved process can be arranged to operate with any of the known forms of "mechanical absorbers" or "centrifugal scrubbers." If such a form of apparatus be used, my process is in no wise changed. An advantage to be gained in the use of centrifugal scrubbers is that the oil and gas are brought into more intimate contact with each other and thus there is a relative freedom from "channeling." Particularly in the case of the use of centrifugal scrubbers, I can operate scrubber 1 to discharge oil containing about 10% of absorbed gasoline, a percentage which is regarded as wastefully inefficient in present methods of absorption. I am enabled to do this, however, because my second and third absorbers prevent loss of gasoline hydrocarbons.

While I have described my invention more particularly in connection with its specific application to the absorption of gasoline hydrocarbons from natural gas by means of an oleaginous absorptive medium at a pressure of 30 lbs. in absorber towers, I desire that I shall not be limited to such a particular application thereof, but intend that the invention shall include such modifications and changes as fall within the appended claims.

In this connection is as desirable to provide heating coils in chambers in which the pressure on the oil is reduced after the oil leaves the absorbers, i. e. chambers 3, 19, 23, 56, 64 and 66, to prevent reduction of the temperature of the oil.

What I claim as new and desire to secure by Letters Patent of the United States is:

1. As a step in the process of deriving gasoline from natural gas by absorption under pressure, reducing the pressure of the absorptive medium between stages of absorption under pressure and thereafter returning the liquid directly to an earlier stage of absorption.

2. In a multistage counter current process of absorbing gasoline from natural gas by a liquid absorptive medium, contacting absorptive medium with only natural gas having relatively low content of gasoline hydrocarbons, partially stripping the absorptive medium and passing the partially stripped medium directly into contact with natural gas having relatively high content of gasoline hydrocarbons.

3. In a multistage process of absorbing gasoline from natural gas by a liquid absorptive medium under pressure, contacting absorptive medium with only natural gas having relatively low content of gasoline hydrocarbons, removing the absorptive medium from contact with the gas and reducing the pressure thereon, restoring the pressure on the absorptive medium and passing the same directly to contact with natural gas having a relatively high content of gasoline hydrocarbons.

4. In a multistage process of absorbing gasoline from natural gas by a liquid absorptive medium under super-atmospheric pressure, contacting absorptive medium with natural gas having relatively low content of gasoline hydrocarbons, removing the absorptive medium from contact with the gas and subjecting it to a sub-atmospheric pressure, restoring the super-atmospheric pressure on the absorptive medium and passing the same directly to contact with natural gas having a relatively high content of gasoline hydrocarbons.

5. In a multi-stage process of absorbing gasoline from natural gas by a liquid absorptive medium under pressure, removing the absorptive medium from contact with the gas before absorption is complete, then partially stripping a part of the medium by single distillation and more completely stripping another part of the medium by multiple distillation, and contacting said parts respectively with bodies of natural gas having relatively higher and lower content of gasoline hydrocarbons.

6. In multi-stage absorption of gasoline from natural gas the process which comprises passing the gas through successive absorption

70

- stages, contacting oil with gas passing through a later absorption stage, then subjecting the oil to a partial stripping operation, and then contacting the partially stripped oil with gas passing through an earlier absorption stage. 70
7. In multi-stage absorption of gasoline from natural gas the process which comprises passing the gas through successive absorption stages, contacting oil with gas passing through a later absorption stage, then subjecting the oil to a partial stripping operation, contacting the partially stripped oil with gas passing through an earlier absorption stage, and then subjecting the oil passing from said earlier absorption stage to a more complete stripping operation. 75
8. In a multi-stage process of absorbing gasoline from natural gas by a liquid absorptive medium under pressure, removing the absorptive medium from contact with the gas before absorption is complete, stripping part thereof partially, and part thereof more completely, and returning said parts into contact with gas of different gasoline hydrocarbon content. 80
9. In the process of separation of vapors by absorption wherein the vapors flow counter-current to a menstruum that flows in a closed cycle and is subjected to a thorough stripping operation at some point of its cycle of flow, the step comprising withdrawing the menstruum from contact with the vapors at an intermediate point of the counter flow thereof, less thoroughly stripping the menstruum, returning it to counter flow relation with the vapors at an intermediate point of the counterflow, and completing said counter-current flow. 85
10. In apparatus for the separation of vapors by absorption, a plurality of absorbers connected for the passage of vapors successively therethrough, means for thoroughly stripping absorptive medium passing from an earlier one of said absorbers, means for passing the absorptive medium so stripped into a later one of said absorbers, means for less thoroughly stripping absorptive medium passing from said later absorber, and means for passing the less thoroughly stripped absorptive medium into said earlier absorber. 90
11. In apparatus for deriving gasoline from natural gas by absorption, means for contacting oil with gas lean in gasoline hydrocarbons, means for partially stripping oil passing from contact with the lean gas, and means for passing the partially stripped oil directly to contact with gas rich in gasoline hydrocarbons. 95
12. In a multiple stage counter current process of absorbing gasoline hydrocarbons from natural gas in a liquid absorption medium, subjecting the absorptive medium to a stripping operation, diverting a part of the flow of the absorption medium, additionally

stripping the diverted part, returning said part to contact with natural gas having relatively lean content of gasoline hydrocarbons and returning the remainder to contact with gasoline having a relatively high content of gasoline hydrocarbons. 100

13. In apparatus for deriving gasoline from natural gas by absorption, means for contacting natural gas with oil previously used to absorb gasoline and from which the gasoline has been partially stripped, means for contacting oil with the residual gas passing from said first named contacting means, means for receiving the oil from said second mentioned contacting means and partially stripping the same, means for delivering the partially stripped oil directly to said first named contacting means and means for thoroughly stripping the oil obtained from said first mentioned contacting means and delivering the same directly to said second named contacting means. 105

14. In a process of separating gases, the steps comprising passing the gases through successive absorption stages, contacting oil with gas passing through a later absorption stage, then subjecting the oil to a partial stripping operation, and then passing the partially stripped oil directly into contact with gas passing through an earlier absorption stage. 110

15. In a process of separating gases, the steps comprising passing the gases through successive absorption stages, contacting oil with gas passing through an intermediate absorption stage, then subjecting the oil to a partial stripping operation, passing the partially stripped oil into contact with gas passing through an earlier absorption stage, then partially stripping and returning to said intermediate stage a part of the oil from said earlier stage, and more completely stripping and passing to a later stage a part of the oil passing from said earlier stage. 115

In testimony whereof, I have signed my name to this specification.
